UNITED STATES PATENT OFFICE.

LEE HARMAN DEANER, OF MUSKEGON, MICHIGAN, ASSIGNOR OF ONE-HALF
TO WILLIAM W. MCLAREN, OF SAME PLACE.

COMBINED HEAD-REST AND CHAIR-SEAT.

SPECIFICATION forming part of Letters Patent No. 673,617, dated May 7, 1901.

Application filed July 25, 1900. Serial No. 24,817. (No model.)

To all whom it may concern:

Be it known that I, LEE HARMAN DEANER, a citizen of the United States, residing at Muskegon, in the county of Muskegon and State 5 of Michigan, have invented a new and useful Combined Head-Rest and Chair-Seat, of which the following is a specification.

This invention relates to a combined head-rest and chair-seat cushion; and the object of 10 the same is to provide simple and effective means for adapting a cushion for use either as a seat-cushion or a head-rest by securing thereto means for supporting it on the back of a chair or analogous device and which will 15 not obstruct or interfere in the least with its use as a seat-cushion and wherein the parts are strong and durable, easily and readily applied, and comparatively inexpensive.

The invention consists in the construction 20 and arrangement of the several parts, which will be more fully hereinafter described and claimed.

In the drawings, Figure 1 is a perspective view of a chair looking toward the rear there- 25 of and showing a cushion supported thereon as a head-rest by the improved attachment. Fig. 2 is a bottom plan view of a cushion, showing the improved device thereon. Fig. 3 is a detail perspective view of the improved 30 attachment shown partially broken away.

Similar numerals of reference are employed to indicate corresponding parts in the several 35 views.

The numeral 1 designates a cushion of any 40 preferred form and general make-up and similar to that ordinarily employed for chair-seat coverings, or it may be the usual form or type of sofa or door-stoop or porch cushion. The expense of this cushion will depend exclu- 45 sively on the desire and demand of the purchaser or user, and it is proposed to either apply the improved attachment, which will be presently set forth, at the time of initial preparation or manufacture of the cushion or to sell or vend the said attachment inde- 50 pendently with explanations as to mode of application, so that individual purchasers may be enabled to attach it to a cushion of their own fabrication.

55 The improved attachment, which conjointly operates with the cushion to make the latter

convertible from one use to another, comprises a support 2, formed, preferably, of sheet metal of any desirable width and length and having opposite rolled or tubular side 55 edges 3 to stiffen the same and provided with intermediate apertures 4 to receive fastening devices, such as upholstering buttons or tufts, to keep the said support in one position in the cushion-body. In the one tubular side 60 edge of the support the longitudinal member 5 of a hanger 6 is movably mounted, the said hanger in the present instance having opposite inwardly-converging side portions 7, with terminal upstanding portions 8 at different 65 angles and from which a curved loop 9 is turned over rearwardly and downwardly, consider- 70 able space being left between the upper portions of the loop and the said terminals to permit the hanger to be applied over the up- 75 per edge of the back of a chair or other device. To prevent marring or scratching the device over which the hanger is applied, the part of the hanger from the opposite ends of the support and external of the bottom or 75 back of the cushion is completely covered with rubber or other suitable buffering material, as at 10.

By having the hanger movably or pivotally connected to the support within the cushion 80 the said hanger is permitted to be pushed closely against the bottom of the cushion when the latter is used as a seat-cushion without bending the hanger or exerting a strain thereon that would have a tendency to break or 85 fracture the point of jointure thereof with the support and which would result if the hanger and support were immovably connected. Furthermore, a material advantage ensues from a movable attachment of the 90 hanger to the support when the improved device is used as a head-cushion in that it is permitted to have a certain amount of movement to adjust itself in relation to a chair-back without the stiffness that would result 95 from a rigidly-connected hanger.

The improved arrangement presents a very 100 convenient combination of parts and adapts a cushion to be used either for sitting purposes on a chair-seat, when the hanger will be disposed beneath, or it may be quickly applied over the back of a chair, as shown, to

make the same cushion serve as a head-rest. It will also be understood that the hanger will have sufficient resiliency to cause it to maintain its shape, and though the preferred form has been shown changes in the shape 5 may be resorted to at will.

Having thus described the invention, what is claimed as new is—

1. A seat-cushion having a support inclosed 10 and immovably fastened within the bottom portion thereof and provided with a tubular edge, and an exteriorly-positioned hanger having a member movably engaging the said tubular edge of the support within the cushion, the hanger being resilient and compressible 15 toward the cushion-bottom.

2. A seat-cushion having a support inclosed 20 and immovably fastened within the bottom portion thereof and consisting of a strip of metal with rolled or tubular edges, and an exteriorly-positioned hanger having a member 25 movably engaging one of the said tubu-

lar edges of the support, and provided also with inwardly-converging side portions from which extends a curved loop, the exterior 25 portion of the hanger being covered with a buffer.

3. A seat-cushion having a support completely inclosed and immovably fastened in the intermediate bottom portion thereof, and 30 a hanger positioned exteriorly of the bottom portion of the cushion and having a portion extended into the latter and movably connected to the support in a pivotal manner, the support being rigid and the hanger 35 resilient and compressible against the bottom of the cushion.

In testimony that I claim the foregoing as my own I have hereto affixed my signature in the presence of two witnesses.

LEE HARMAN DEANER.
